UNITED STATES PATENT OFFICE.

CHARLES H. TOMLINSON, OF MANSFIELD, OHIO, ASSIGNOR TO THE TOMLINSON COUPLER COMPANY, OF DENVER, COLORADO, A CORPORATION OF SOUTH DAKOTA.

EMERGENCY BRAKE ATTACHMENT.

1,288,294.

Specification of Letters Patent. Patented Dec. 17, 1918.

Application filed July 29, 1918. Serial No. 247,229.

To all whom it may concern:

Be it known that I, CHARLES H. TOMLINSON, a citizen of the United States, residing at Mansfield, in the county of Richland and State of Ohio, have invented certain new and useful Improvements in Emergency Brake Attachments, of which the following is a specification.

This invention relates to mechanism for automatically applying the brakes of one or more of the cars of a train when the drawbars between two cars are rotated beyond a predetermined point, and the principal object of the invention is to provide a mechanism for accomplishing this result, together with means for permitting the release of the brakes.

The invention consists in the novel construction, combination and arrangement of the parts.

In the accompanying drawings, Figure 1 is a view of an emergency brake attachment for air brakes as applied to the underside of a car; Fig. 2 is a detail view of a portion of said mechanism; Fig. 3 illustrates a modification; Fig. 4 is a detail of the construction shown in Fig. 3; Fig. 5 illustrates a modification for applying an electric brake; Fig. 6 is a detail of the construction shown in Fig. 5; and Fig. 7 shows the positions of certain of the parts when two cars split a switch.

When a railway switch is turned between two connected cars of a train either by accident or design, causing them to move or be moved on different tracks, it is called splitting the switch, and unless the cars are stopped or disconnected serious damage is bound to occur either to the car couplers, or the track. The present invention overcomes this difficulty by providing means for automatically setting the brakes and stopping the cars when the car drawbar reaches a predetermined angular position. In the case of street cars it is desirable also to limit the angular movement of the drawbar so that no portion of the car structure, such as the steps which are usually located at the ends of the car, will be struck and damaged by the drawbar.

In the construction shown by Figs. 1 and 2 a drawbar 1 is pivoted adjacent the end of a car 2 and is provided with a guide rail 3 to support it in its swinging movement.

This drawbar is for the purpose of connect-

ing adjacent cars and must be pivoted to allow the swinging movement of the cars when they are upon a curve.

Carried by the car, adjacent the end thereof, is an air brake pipe line 4 which is connected to the air brake mechanism, not shown, and this pipe line is provided with two valves 5 and 6 for opening the pipe line to the atmosphere and in thereby applying the brakes in a well-known manner. These valves are preferably of the type which has an arm 7 that is parallel with the pipe when the valve is open, and at right angles to it, as shown in Fig. 1, when the valve is closed.

Attached to the arm of the valve 5 is a manually operable handle 8 which extends adjacent the side of the car where it may be grasped and operated. Attached to the arm 7 of the valve 6, which is between the valve 5 and the end of the pipe 4, is a flexible cable or chain 9 having two sections 10 each of which passes over a pulley 11 and is connected to an arm 12 at one end of the guide rail 3. The arms 12 are each held normally in position by means of a bolt 13 which extends through the guide rail. That portion of the drawbar which supports it from the guide rail 3 comprises a hanger 14 which extends over the edge of the guide rail and is adapted to engage either of the arms 12 when the drawbar 1 is rotated to either end of the guide rail 3. The engagement of the hanger 14 with either arm 12 causes the holding bolt 13 to be broken or sheared off and the arm 12 to be turned, which pulls on the chain 9 attached thereto, rotating the arm 7 of valve 6 until the valve is open. This opens the brake line and applies the brakes and prevents further movement of the car until the brake is released. The valve 5 is normally open, and in order to release the brake the pipe line 4 must be closed and, therefore, it is necessary only to close the valve 5 by the manual operation of the handle 8 which enables the pressure to be built up in the brake line and the subsequent release of the brakes. The valve 6 and the operating arm 12 can be reset immediately, or they may be set at some later time.

In the form shown by Figs. 3 and 4 the operating chain 9 is dispensed with, and the air brake pipe line is provided with extensions 15 which terminate adjacent the opposite ends of the guide rails 3, and at

each end is a valve 16 attached to the guide rail and having an operating arm 17 overlapping the inner edge of the rail and normally held in place by a frangible bolt 18 so that the hanger 14 of the drawbar directly engages the arm 17 and opens the valve 16 at either end of the guide rail. In this form a resetting valve 5 with an operating handle 8 is also provided.

10 Some cars may have electro-responsive brakes, and in such cases the drawbar, instead of operating a valve near the limits of its travel, operates an electric switch, as shown in Figs. 5 and 6. The brake device proper is not shown, but an electric circuit-making device for controlling the brake is mounted near each end of the rail 3, comprising a cam 19 pivoted on the rail with a frangible bolt 20 for holding the cam normally in position to be engaged by the overlapping edge of the hanger 14 of the drawbar 1. A bracket 21 is attached to the car body, in which a bolt 22 is slidable and pressed against the cam 19 by means of a spring 23 interposed between one arm of the bracket and a contact bar 24 secured to the bolt. This contact bar is adapted to connect fixed contacts 25 to which the conductors 26 are attached whenever the drawbar is swung far enough in either direction to operate either of the cams 19, thus causing a movement of the electric switch to energize the electro-responsive brake.

30 In all of these forms it is obvious that the brakes may be applied before the drawbar is rotated sufficiently to engage the steps, which in street car construction are usually located near the ends of the guide rail 3. It is to be understood, furthermore, that although reference has been made to a single car, the operation of splitting the switch occurs only between two coupled cars, and as it is common practice in operating trains or cars to have brake lines connected between all of the cars, whether they be motor cars or trailers, so that the operation of the emergency device of one of the cars, whether it be for air or electric brakes, sets the brakes in all of the cars since they are connected 40 for operation together.

45 In a switch splitting operation one of two connected cars A and B, as shown in Fig. 7, is directed from a main track T to switch connected track S, and the other car B remains on the main track T, so that as the cars continue they finally reach a position such that the connected drawbars 1 would strike the steps of one of the cars, or any other parts that might be in the way. The 55 continued operation would either tear one of the cars loose from its truck or from the track, causing much damage and inconvenience, perhaps tying up the lines until repairs could be made. By employing the 60 present invention an accident of this kind

is avoided by interposing a device in the path of the drawbars on both cars so that the car brakes upon either or both cars are set to stop the cars before any damage occurs to them. In the case of an air brake the 70 devices may serve to open a connection to atmosphere, as shown by Figs. 1 to 4, and as shown by Figs. 5 and 6, to close an electric circuit for energizing an electroresponsive device which may be either a brake or a 75 visual signal for the car operator.

I claim:

1. The combination with a valved air brake line, of a pivoted drawbar, and means dependent upon the movement of the drawbar for operating the air brake valve.
2. The combination with a valved air brake line, of a pivoted drawbar, and means dependent upon the rotation of the drawbar for automatically operating the air 85 brake valve to apply the brake.
3. The combination of a car for train coupling and comprising a pivoted drawbar, and an air brake including a valved air brake line; and means dependent upon a switch-splitting rotation of the drawbar to operate the air brake valve for applying the brake.
4. The combination with an air brake line including a valve therein, of a car carrying the brake line having a pivoted drawbar, and means operated by the rotation of the drawbar a predetermined amount to open the said valve for applying the brake.
5. The combination with a car having a 100 pivoted drawbar; and an air-brake line with an atmospheric valve, means for opening the valve upon a predetermined movement of the drawbar to apply the brake, and means for closing the air brake line to reset the 105 brakes.
6. A car having a pivoted drawbar, and a valved air brake line in combination with means operated by a predetermined movement of the drawbar to open the valve or 110 applying the brake.
7. The combination with a car having a pivoted drawbar and an air brake pipe line with a valve adjacent the end thereof, means for opening the valve to apply the brake 115 upon a predetermined movement of the drawbar, and a resetting valve in the pipe line at a greater distance from the end thereof than the other valve which may be manually operated at will.
8. The combination with a car having a pivoted drawbar and a guide rail for supporting it, an air brake pipe line comprising valves to open the pipe line to atmosphere, and means comprising an arm engageable 125 by the drawbar for operating the said valve to open the pipe line to atmosphere.
9. The combination with a car having a pivoted drawbar and a guide rail for supporting it, an air brake pipe line comprising 130

ing valves to open the pipe line to atmosphere, and means comprising an arm engageable by the drawbar, and a frangible connection for operating the said valve to open the pipe line to atmosphere.

10. The combination with a car having a pivoted drawbar and means for applying the car brakes, of a device operated by the drawbar for actuating the said means.
- 10 11. The combination with a pair of coupled cars having pivoted drawbars and means for applying the car brakes, of a device carried by one of the cars and actuated by one of the drawbars to operate said means.
- 15 12. The combination with a car having a pivoted drawbar, a carrying rail, and a car-

rier for the drawbar overlapping the edges of the rail; of a brake applying device comprising a rotatable member engageable by 20 said carrier when the drawbar is rotated a predetermined distance from its central position.

13. The combination with a car having brakes, of emergency means for applying 25 them; said means comprising a pivoted car connecting member, and a device engaged thereby which actuates the means when said member is sufficiently rotated.

In testimony whereof I have signed my 30 name to this specification on this 11th day of July A. D. 1918.

CHARLES H. TOMLINSON.
